UNITED STATES PATENT OFFICE

2,475,071

PESSARY

Thomas Young, New York, N. Y., assignor to
 Durex Products, Incorporated, New York, N. Y.,
 a corporation of New York

Application November 27, 1946, Serial No. 712,607

2 Claims. (Cl. 128—127)

1

This invention relates to pessaries, and more particularly to pessaries of specialized shape for use by gynecologists and obstetricians in the correction or prevention of certain conditions of the female genital organs.

In cases of cystocele, for example, it is desirable to use a pessary, somewhat elongated in shape, and whose rim portion provides longitudinal rigidity in order to offer support to the overhanging tissue. To facilitate the adjustment of the pessary to conform to the contour of the retropubic arch, it is further desirable that the rim portion of the pessary include a relatively flat flexible portion intermediate the rigid longitudinal portions. The resulting shape is generally similar in appearance to a horseshoe, the rigid portions of the periphery forming the toe and sides of the horseshoe with the relatively flat flexible portion joining the two heels.

In order to permit the pessary to be folded for insertion in the vaginal cavity, another flexible portion is included in the periphery of the pessary and is preferably located centrally at the toe of the horseshoe shape.

It is, therefore, an object of the invention to provide a pessary which may be either of the ring or open type or of the occlusive type and which is substantially in the form of a horseshoe with closed ends.

A further object is to provide a horseshoe shaped pessary comprising rigid longitudinal members adapted to provide the required shape.

Another object of the invention is to provide a horseshoe-shaped pessary comprising longitudinal rigid portions to provide the required shape and including flexible portions adapted to permit folding of the pessary to facilitate its insertion into the vaginal cavity.

Other and further objects will become apparent upon reading the following specification, reference being had to the accompanying drawings which form a part hereof.

Referring to the drawings

Fig. 1 shows a side view of an embodiment of the invention;

Fig. 2 shows a plan view of the embodiment of Fig. 1, partly broken away;

Fig. 3 is a perspective view of the embodiment of Fig. 1 shown folded for insertion in the vagina;

Fig. 4 shows a side view of the embodiment of Fig. 1 in a laterally compressed condition to which it will expand after insertion;

Fig. 5 is a perspective view showing the shapes of the rigid members used in the embodiment illustrated in Figs. 1 to 4;

2

Figs. 6 to 11 show perspective views of modifications of the members of Fig. 5, each adapted to provide a modified form of horseshoe shape.

Referring to Fig. 1, the pessary comprises a rim portion 12, and if the pessary is of the occlusive type, a flexible dome portion 13 preferably of impermeable material which may be rubber, for example. The rim portion 12 is preferably of the same material.

10 As shown in Fig. 2, the rim portion 12 comprises a helical spring 14 which extends around the entire periphery of the pessary. Spring 14 is coated with or enclosed in suitable flexible impermeable material. Situated within helical spring 14 are two core members 15 and 16 shaped substantially as indicated in Fig. 5 and of sufficient rigidity to cause the pessary to maintain, when uncompressed, the shape shown in Fig. 2. If desired, core members 15 and 16 may be of material such as wire which will be capable of being manually formed into any desired shape, but which initially will have a form substantially as shown in Fig. 5.

In some instances, it may be desirable for the 25 cores 15 and 16 to have one of the modified shapes shown in Figs. 6 to 11.

In order to maintain the cores 15 and 16 in their correct relative positions within the helical spring 14, additional springs such as 17 and 18 30 may be utilized within helical spring 14 which will serve to provide resiliency, permitting the pessary to be folded and at the same time will maintain the cores in their correct relative positions. Other suitable means for maintaining the cores 35 in correct position are set forth in my copending application, Serial No. 613,131, filed August 28, 1945, now Patent Number 2,443,943.

In general, it will be noted that each of the 40 two cores has a sharp bend through an angle of the order of 90° and at the other end, a curvature preferably somewhat elliptical and having radii of curvature substantially greater than the radius of curvature of the 90° bend.

When these cores 15 and 16 are placed in the 45 spring 14 it is usually preferable to have the ends of these elliptical curves separated from one another by a short distance of the order of about one-quarter of an inch, so that on laterally compressing the spring not too sharp a bend is obtained. I prefer to have the other leg of the 50 sharp angle of each core relatively short compared to the curved end. This provides a considerable space between these two ends in the 55 finished spring, so that not too sharp a bend is obtained when the pessary is laterally compressed.

The short end of the insert may be bent in the same plane as the curve or in a different plane. The curved portion may be all one plane or may be in more than one plane.

In operation, considering the embodiment of the invention as shown in Figs. 1-5, before compressing, the entire spring of the pessary is entirely in one plane. When it is laterally compressed it assumes the shape shown in Figure 3. This is very advantageous in that it provides a curve which follows the shape of the vaginal canal and therefore has a contour suitable for gynecological insertion. When, after insertion, the lateral pressure is removed, the pessary opens up and when adjusted at the forward end, since it still remains under slight lateral pressure, it assumes the shape shown in Figure 4.

I have described what I believe to be the best embodiments of my invention. I do not wish, however, to be confined to the embodiments shown, but what I desire to cover by Letters Patent is set forth in the appended claims.

I claim:

1. A substantially horseshoe shaped pessary having a continuous rim portion comprising a pair of oppositely disposed relatively rigid core members, each extending in a sweeping curve from a point near the toe to a corner of the heel and thence sharply inward, said core portions being but slightly spaced from one another within the rim at the toe portion sufficiently to permit lateral collapse of the pessary, but being connected through a comparatively long, normally substantially straight flexible rim portion at the heel, the pessary being constructed and arranged to assume a curvature when collapsed corresponding to that of the vaginal canal.

2. A substantially horseshoe shaped pessary having a continuous rim portion comprising a pair of oppositely disposed, relatively rigid core members, each extending in a sweeping curve from a point near the toe to a corner of the heel and thence sharply inward, a substantially continuous helical spring surrounding the core portions and extending through the spaces that intervene between the adjacent ends of the core portions, said core portions being but slightly spaced at the toe portion sufficiently to facilitate lateral collapse of the pessary, but being connected through a comparatively long, normally substantial straight flexible portion at the heel, the pessary being constructed and arranged to assume a curvature when collapsed corresponding to that of the vaginal canal.

THOMAS YOUNG.
